GAS HEATER FOR CURLERS

Stanley Blenden, New York, N. Y.

Application December 5, 1936, Serial No. 114,483

6 Claims. (Cl. 126—234)

This invention relates to a gas heater for curling tongs for the hair. The usual form of gas heater for hair curling tongs or curler consists merely of a burner and a rack on which to rest the curler. It is necessary to keep the burner going all during the hair curling operation regardless of whether the curler is being heated, used on the hair or cooled. This is very uneconomical. The principal object of this invention is to economize in the use of the gas, and it is characteristic of the invention that when the curler is placed in the holder the burner is lit, and when the curler is lifted off, the burner is shut off.

15 In the drawing,

Fig. 1 is a longitudinal view in elevation with the frame broken away on the line 1—1 of Fig. 2, showing a heater made in accordance with my invention, the curler being shown in dotted lines in heating position, and the operating arm in solid lines in cut-off position;

20 Fig. 2 is a plan view of the heater with the curler in cooling position; while

Fig. 3 is a sectional view across the burner, taken on the line 3—3 of Fig. 2.

25 In order to devise an automatic gas cut-off and lighter for a hair curler, I have found that it is necessary to make use of the full weight of the curler acting against a tension spring of appreciable strength to control the gas cock, and it is also necessary to turn the gas cock through a considerable arc for the usual opening and closing movement. With these facts in mind, I have devised the following heater.

30 The burner consists of a horizontal perforated pipe 5 screwed on the air intake 6, the latter being attached to the gas supply through the gas cock 8. The burner is long enough to heat the tongs of the curler. Projecting upwardly from the gas cock 8 but between the cock proper and the gas supply 7, is a screw valve 9 for a gas pilot light 10. It will be noted that the pilot is never shut off. The pilot extends above the air intake to a position above the holes 11 in the burner 5. 35 It should be understood that any other desired type of pilot light such as a friction type of lighter actuated by the operating arm described below, can be used. Also, a chemical type of pilot can be used.

40 Surrounding the burner is a hollow rectangular holder or frame 12 which may be open at the bottom. The burner extends longitudinally therein near the bottom and is held by a set screw 13. It will be noted that the burner preferably is not centrally located but is adjacent one

side of the frame. The upper end and side portions 14, 15 of the frame may be sloped inwardly a little, as shown in the drawing, if desired. The top of the frame is preferably flat. To receive the curler when it is to be heated, the frame has a slot cut in it from end to end above the burner 5. This slot provides rests 16, 17 at the gas supply end and the outer end respectively of the frame, and the proper distance above the burner to heat the curler. These rests are about the level 5 where the sloping upper portions 14 of the ends join the vertical portions. The slot is wide enough to take the tongs 18 of the curler but not the center 19 about which the tongs pivot. The center of gravity of the ordinary curler is at or 10 about this hinge center 19. To get the benefit of the entire weight of the curler for operating the gas cock, there is a stiff wire operating arm 20 attached to the rotatable member of the gas cock 8 which extends through one end of the frame 15 parallel to the burner and beyond the latter where its end underlies the curler adjacent the rest 17, at the opposite or free end of the burner from the gas cock. This brings the point of contact between the operating arm and the curler 20 very close to the center of gravity of the latter, and as a result practically the entire weight of the curler rests on the arm. It will be noted that the bend in the handles of the ordinary curler prevents the curler from being inserted so far 25 in the heater as to lose the full benefit of the weight of the curler to control the gas cock. A tension spring 21 connected between the arm 20 and the under side of the top of the frame is 30 capable of pulling the arm 20 upwardly and operating the gas cock to close it. The weight of the curler is sufficient to open the gas cock against 35 the pull of the spring.

40 It will be observed that owing to the length of arm necessary to reach the center of gravity of the curler, a considerable movement of the end of the arm is needed to operate the gas cock. For this reason the end of the arm underlying the curler is bent upwardly in the form of a high step 22 adapted to project upwardly through the slot when the curler is removed. (See the solid line position in Fig. 1.) Owing to this high step 45 when the curler is laid in the slot the arm is depressed all the way to the bottom of the frame, this giving the maximum travel. (See the dotted line position in Fig. 1.) The flat top of the frame is adapted to form a rest for the curler when not 50 in use or when cooling.

55 To use the heater the screw valve 9 is opened, the pilot lighted and that flame adjusted. The 55

curler is then brought above the heater with the end of the tongs toward the gas cock and lowered onto the high step 22 and the rests 16, 17. The pivot center 19 of the curler should be placed adjacent the corresponding sloping end 14 of the frame. The depressing of the operating arm 20 by the weight of the curler opens the gas cock 8 and the pilot 10 lights the burner 5. When the curler is needed it is lifted out of the slot and off the high step of the operating arm. The tension spring thereupon operates the arm 20 to close the gas cock and the flow of gas to the burner is stopped. The pilot light remains on. Obviously with this automatic cut-off only gas for the pilot light is burned except when the curler is to be heated.

What I claim is:

1. A gas heater for a hair curler, comprising a frame having a slot therein to receive the curler, 20 a burner mounted under the slot and a gas cock adjacent one end of the frame, in combination with an operating arm for the gas cock having a portion lying in the slot at a point beyond the burner and adapted to be depressed when the 25 curler is placed in the slot.

2. A gas heater for a hair curler, comprising a frame having a slot therein to receive the curler, a burner mounted under the slot and a gas cock adjacent one end of the frame, in combination 30 with an operating arm carried by the gas cock extending beside the burner, and a tension spring tending to keep the arm in raised position, there being a high step on the arm projecting upwardly through the slot above the frame and adapted to 35 be depressed when the curler is placed over the burner.

3. A gas heater for a hair curler, comprising a frame having a slot therein to receive the curler, a burner mounted under the slot and a 40 gas cock adjacent one end of the frame, in combination with an operating arm carried by the gas cock extending beside the burner, and a tension spring tending to keep the arm in raised position, there being a high step on the arm projecting upwardly through the slot above the frame 45 at a point beyond the holes in the burner and adapted to be depressed when the curler is placed over the burner.

4. A gas heater for a hair curler, comprising a gas cock, an operating arm attached to the cock and a burner on said cock, in combination with a frame having a slot therein over the burner forming rests for the curler between the burner and the cock and also beyond the free end of the burner, said slot being too narrow to receive the hinge point of the ordinary curler, said operating arm being adapted to contact the curler beyond the free end of the burner and to be actuated thereby to open the cock, and a tension spring to actuate the arm in the opposite direction upon removal of the curler.

5. A gas heater for a hair curler, comprising a frame having a slot therein to receive and form 15 rests for the curler, a burner mounted under the slot and a gas cock adjacent one end of the frame, in combination with an operating arm carried by the gas cock and a tension spring tending to keep 20 the arm in raised position, there being a high step on the arm projecting upwardly above the frame beyond the free end of the burner and adapted to be depressed to the level of the rests in the frame when the curler is placed over the burner, the slot in the frame being too narrow 25 to receive the hinge point of the ordinary curler whereby the point of contact between the step on the arm and the curler will be close to the center of gravity of the latter.

6. A gas heater for a hair curler, comprising 30 a gas cock, a burner on said cock and an operating arm attached to the cock, in combination with a flat-top frame having a slot therein over the burner, said slot being too narrow to receive the handles of the ordinary curler, the operating 35 arm being adapted to contact the curler beyond the free end of the burner and to be actuated thereby to open the cock, and a tension spring to actuate said arm in the opposite direction upon removal of the curler, said frame forming one rest 40 for the curler between the cock and the burner and another rest sufficiently beyond the free end of the burner to be close to the center of gravity of the curler and thereby avoid the necessity 45 for any support beyond the frame.

STANLEY BLENDEN.
